UNITED STATES PATENT OFFICE.

HERMANN MÜLLER, OF LEIPZIG, GERMANY.

TELPHERAGE SYSTEM.

941,938.

Specification of Letters Patent. Patented Nov. 30, 1909.

Application filed February 7, 1906. Serial No. 300,804.

To all whom it may concern:

Be it known that I, HERMANN MÜLLER, engineer, subject of the German Emperor, residing at Leipzig, Germany, have invented 5 new and useful Improvements in Telpherage Systems, and do hereby declare the following to be a full, clear, and exact description of my invention.

Carriages with hoisting apparatus, as employed for electrically driven suspended railway cars, generally require seven conductors for the electrical conveying, hoisting and lowering of loads. It is difficult, often impossible, to employ switches in the 10 tracks of these railways. Besides, the seven conductors are expensive in first cost as well as in maintenance.

The object of the present invention is to reduce the number of conductors for electrically driven suspended railway cars and to employ only two current conductors with the rail for return conductor, also to separate the regulating of the electrical current-taking from the regulating of the mechanical operations. The regulating of the electrical current taking is done by hand by means of a starter fixed at any place of the line. The mechanical movements are regulated by a magnetic current-closer in the 15 carriage and actuated by current impulses given at the starter. Movable starters connected with the conductors by line contacts may also be used at any point of the electrically driven suspended railway with the 20 same results. It is only necessary to provide the necessary contacts at such places where the regulating is intended.

One of the free conductors serves as current conductor for the motors and the other 25 for the circuit closing arrangement. The changing of the current from the driving motor to the hoisting motor is effected by a cylindrical circuit closer which is revolved by means of a ratchet and an electric magnet 30 and which electric magnet receives its current from the conductor for the circuit closing arrangement.

In the accompanying drawing Figure 1 shows a sketch of the car and Fig. 2 shows 35 the arrangement of the circuit closing.

Referring to the drawing, A—A indicates the suspended rail on which the car is running, B is the driving motor of the car, C the hoisting motor, D the circuit closer, E the magnet for the circuit closer, F the magnet 40 for the brake, G the circuit cut-out, H

the current collector for the power conductor, J the current collector for the conductor of the circuit closer and K the hoisting gear.

The wire system consists of the supply line L—L; the power line M—M and the circuit closing line N—N. The line N—N is necessary only at places of loading and discharging.

Arriving at a loading place, the current collector J runs on to the circuit closing line and leaves the same again on leaving the loading place. The current collector H is always in contact with the power line M—M.

O—O is an insulated piece of the power line M—M at the loading place. P—P is a corresponding piece of the circuit closing line N—N.

Q is a starting box with a number of resistances. The slide contact R is connected with the circuit closing line N—N. In Fig. 2 the starting box is connected with the lines by the contact S. The object of this contact is to permit the exchange of the resistance 50 and the connection of the same at different places in the case there are more than two loading places which are not at work at the same time. The current for the two insulated pieces of line O—O and P—P is supplied through the starting box Q from the supply line L—L.

The cylindrical circuit closer has a number of fixed contacts 1 to 8 which are connected by wires with the correspondingly 55 named poles and the current collectors H to L. The connection of the different poles is done by a revolving cylinder whose contacts are shown developed in Fig. 2.

T is a ratchet wheel on the shaft of the 60 cylindrical circuit closer, which is actuated by pawl U and the magnet E. The contacts of the cylindrical circuit closer are arranged to correspond with the consecutive movements of the carriage and the hoisting apparatus.

The developed surface of the cylinder shown in Fig. 2 is an example of a simple conveyor line with two terminals at which 65 loads are hoisted and lowered.

Suppose a loaded car is coming from the left hand side and arrives at the right hand terminal. The consecutive movements produced, after the attendant has closed and opened the circuit closer Q once, are as follows: 1, lowering of the load and discharging of same; 2, hoisting of the empty hook;

3, depart to the left for the loading terminal; 4, lowering of the empty hook; 5, hoisting of the attached load; 6, trip to the right for the discharge terminal. Hereby 5 can be assumed that one separate circuit 10 starter Q for each discharging and loading place, is provided for, or the same circuit 15 starter is used first at the loading place and then at the discharging place.

10 Referring to the single movements of circuit closing diagram we have: The car coming from the left to the right, runs on to the piece of line O—O which is without current and stops there. Now, the attendant closes 15 the starting box Q, the magnet receives current by way of L—R—P—J and turns the circuit closing cylinder D one notch farther, that is, from going to the right to lowering. The hoisting motor receives current in the 20 direction of lowering and the load will be lowered. After the load has been lowered to the desired height, the attendant disengages the starting box, whereby the load is stopped under the action of brake F. After 25 the load is unhooked, the attendant closes the starting box again, whereby magnet E receives current. Hereby the cylinder is turned another notch to connect for hoisting and the load will be hoisted until the auto- 30 matic circuit cut out G cuts out the current for the hoisting motor C. The switch is switched off by the ascending rope V² on which is a weight V' and a hook V to which the load is attached, by means of a lever 35 W. The conduction to the hoisting motor from fixed contact 5, which comes in question for lifting, is consequently interrupted, and the hoisting motor becomes currentless, the electrical brake F comes into action, and 40 the load is brought to a standstill. It will be noticeable that the lever W is fastened on a pivot on which the end cut-off G is also arranged. When the hook acts again after 45 disengagement of the brake, the lever W will fall on account of the weight W' being

brought to bear upon it, and by this means the end cut-off G with its contact is pressed on the fixed contact so that the current circuit for the winch motor is closed. If the rope is now again wound up, the rope weight 50 V' presses in the highest position of the load hook V the lever W on the case. The end cut-off G is removed from the fixed contact and the current interrupted. The attendant then only disengages the starting 55 box and closes it again. The cylinder is turned one notch farther and the contacts are made for the driving motor to go to the left. The car runs to the loading terminal at the left and stops there on arriving at a 60 piece of track O—O without current. The circuit closings of lowering and hoisting are repeated and the car which has taken up the load before hoisting returns to the discharging place. 65

What I claim is:

In a circuit closing arrangement for electrically driven suspended railway cars, the combination of a carriage provided with a carriage motor, and with hoisting gear, a 70 main current conductor L—L, a working conductor M—M for the carriage motor with insulated sections where movements are to be carried out, an auxiliary conductor P—P for the insulated section fed from the main 75 conductor L—L, a magnet E in the carriage supplied with current from the auxiliary conductor, a ratchet wheel and pawl T—U actuated thereby, a cylindrical circuit closer D connected therewith, and a starting box Q 80 together with contacts for connection with said starting box placed at suitable points in the main supply line, substantially as and for the purpose described.

In witness whereof I have signed this 85 specification in the presence of two witnesses.

HERMANN MULLER.
